PICKER STICK CHECKING MECHANISM

Walter J. Budzyna, East Douglas, Mass., assignor
to Draper Corporation, Hopedale, Mass., a cor-
poration of Maine

Application February 19, 1944, Serial No. 523,040

7 Claims. (Cl. 139—165)

The present invention relates to picking mechanisms for fly shuttle looms and, as illustrated herein, relates more particularly to picker stick checking mechanisms.

One prior type of picker stick checking mechanism comprises a depending support attached to the lay beam and causing a flexible check strap loop within which the picker stick oscillates and which is engaged and moved by the picker stick at each end of its oscillation. In devices of this type, it is necessary to provide friction means for retarding the movement of the strap and also to provide readily accessible adjusting means for said friction means. In such prior devices, it has not been possible conveniently and accurately to adjust the friction means and hence proper checking of the picker stick has not always been effected.

One object of the present invention, accordingly, is to provide a picker stick checking mechanism wherein the friction means may be conveniently and accurately adjusted. To this end, the friction means includes a bracket secured to the lay having a downwardly extending finger, a supporting member having a downwardly extending finger, said supporting member being movable relatively to the first mentioned finger, and means for securing the supporting member to the bracket, said means including an eccentric for determining the adjusted position of said supporting member.

With the above and other objects and features in view the invention will now be described with particular reference to the accompanying drawing which illustrates a preferred embodiment of the invention and in which:

Fig. 1 is a view in front elevation of a picker checking mechanism embodying the present invention;

Fig. 2 is a plan view of the device shown in Fig. 1;

Fig. 3 is a vertical sectional view taken along the line III—III of Fig. 2;

Fig. 4 is a view taken along line IV—IV of Fig. 2; and

Fig. 5 is a sectional view taken along the line V—V of Fig. 2.

The drawing shows but a part of a loom having the invention applied thereto. The parts which are not shown may be of any usual construction and form no part of the present invention.

The drawing shows a portion of the left hand end of a usual lay beam 10. The lay beam at its end is provided with the usual shuttle box (not shown) into and out of which the shuttle is picked by a picker stick 12. The picker stick 12 oscillates in the slot 14 in the usual manner.

The lay is provided with a check strap 16, the

ends thereof being clamped and supported in a bracket 18 of usual construction fixed to and supported by the lay beam 10 by bolts 20.

A second bracket 22 is secured to the other side 5 of the lay opposite to the bracket 18 and provides means for supporting and checking the movement of the strap. The bracket 22 has a portion 24 which extends below and fits against the bottom of the lay 10 and has a flange 26 which extends upwardly against the front side of the lay. The bracket 22 is secured to the lay by bolts 28 which extend through slots 30 formed in the portion 24.

The portion or bed plate 24 is provided with 15 a depending finger 32, which is provided with a rounded strap engaging face which engages the inner surface of the check strap 16. The finger 32 is provided at its lower end with a forwardly extending flange 34 which supports and prevents 20 downward movement of the strap when it is loose or is being adjusted.

The bracket 22 is provided with a forwardly extending flange 36 which is provided with a drilled hole for receiving an adjusting and holding bolt 38. The lower end of the bolt is provided with an eccentric head 40. The bolt 38 at its upper end portion is slabbed off at opposite sides to provide means which can conveniently be engaged by a wrench to turn the bolt to obtain the desired adjustment.

The eccentric head 40 fits into a transverse slot 42 formed in the forwardly extending portion 44 of an adjustable bracket 46. The bracket 46 is provided with a depending friction finger 48 which is provided with a rounded rear face which engages the outer surface of the check strap 16. Thus, as best shown in Fig. 2, the check strap 16 takes a sinuous path between the friction fingers 32, and 48. The bracket 46 is provided with an upwardly projecting rib 50 which fits into a groove 52 formed in the lower surface of the forwardly projecting portion 36 of the bracket 22 and forms a convenient means for preventing undesired transverse movement between the parts and serves also as a guide for the forward and rearward adjusting movement of the bracket 46.

The bracket 46 is provided with a forwardly and rearwardly extending slot 54 through which the bolt 38 extends. The slot 54 at its lower end opens into the transverse slot 42. Thus when the bracket 46 is moved rearwardly or forwardly to adjust the position of the finger 48, the bolt 38 remains in position but the bracket 46 is permitted to move relatively thereto. As the bracket 46 and the depending finger 48 thereon are moved rearwardly, the sinuous path or course of the strap is increased and the friction of the strap is correspondingly increased. The position of the bracket 46 is positively and accurately controlled

by the eccentric head 40, and, when the desired adjustment has been made, the bolt is locked in adjusted position by a clamping nut 56. By the use of the above construction accurate control of the retardation of the longitudinal movement of the check strap 16 is effected.

Having thus described a preferred embodiment of the invention, what I claim as new and desire to secure by Letters Patent of the United States is:

1. A friction device for a picker stick check of the type including a flexible looped strap supported beneath the lay and within which the picker stick oscillates, said device including a bracket fixed to the lay and having a depending friction finger adapted to engage the inner face of said strap, a supporting member adjustably secured to said bracket and having a depending friction finger adapted to engage said strap, and adjusting means for positioning the second friction finger relatively to the first friction finger, said adjusting means comprising a member rotatably mounted in said bracket and having a portion engaging said second bracket for moving said supporting member into adjusted position, and means for locking said adjusting means in adjusted position.

2. A friction device for a picker stick check of the type including a flexible looped strap supported beneath the lay and within which the picker stick oscillates, said device including a bracket fixed to the lay and having a depending friction finger adapted to engage the inner face of said strap, a supporting member adjustably secured to said bracket and having a depending friction finger adapted to engage said strap, and a transverse slot, an adjusting member rotatably mounted in said bracket and having an eccentric portion fitting into said slot to move said supporting member into adjusted position when said adjusting member is rotated, and means for locking the adjusting member in adjusted position.

3. A friction device for a picker stick check of the type including a flexible looped strap supported beneath the lay and within which the picker stick oscillates, said device including a bracket fixed to the lay and having a depending friction finger adapted to engage the inner face of said strap, a supporting member adjustably secured to said bracket and having a depending friction finger adapted to engage said strap, and a transverse slot, an adjusting and clamping member having a threaded portion extending through an opening in said bracket and having an integrally formed eccentric fitting into said slot to move said supporting member into adjusted position when said adjusting member is rotated, and a locking and clamping nut cooperating with said threaded portion to secure the adjusting member in adjusted position.

4. A friction device for a picker stick check of the type including a flexible looped strap supported beneath the lay and within which the picker stick oscillates, said device including a bracket fixed to the lay and having a depending friction finger adapted to engage the inner face of said strap, a supporting member adjustably secured to said bracket and having a depending friction finger adapted to engage said strap, and a transverse slot, a rotatable adjusting member

mounted in said bracket and having an eccentric formed on its lower end and fitting into said transverse slot to move said bracket forwardly and rearwardly into adjusted position when said adjusting member is rotated, and a nut for securing the adjusting member in adjusted position.

5. A friction device for a picker stick check of the type including a flexible looped strap supported beneath the lay and within which the picker stick oscillates, said device including a bracket fixed to the lay and having a depending friction finger adapted to engage the inner face of said strap, a supporting member adjustably secured to said bracket and having a depending friction finger for engaging said strap and a transverse slot, a rotatable adjusting member mounted in said bracket and having an eccentric formed on its lower end and fitting into said transverse slot to move said supporting member forwardly and rearwardly into adjusted position when said adjusting member is rotated, and a nut for securing the adjusting member in adjusted position.

6. A friction device for a picker stick check of the type including a flexible looped strap supported beneath the lay and within which the picker stick oscillates, means secured to the lay for supporting the strap, a bracket attached to the front of the lay and having a depending friction finger for engaging the inner surface of the strap, said bracket having a forwardly extending portion, a member detachably secured to said bracket and having a depending friction finger for engaging the outer surface of said strap, said member having a transverse slot and a forwardly and rearwardly extending slot, an adjusting member having a threaded upper end extending through an opening in the forward portion of said bracket and through said forwardly and rearwardly extending slot in said member, said adjusting member having an eccentric at its lower end fitting into said transverse slot to cause forward and rearward movement of said adjusting member into adjusted position, and means for locking said adjusting member in adjusted position.

7. A friction device for a picker stick check of the type including a flexible looped strap supported beneath the lay and within which the picker stick oscillates, means secured to the lay for supporting the strap, a bracket attached to the front of the lay and having a depending friction finger for engaging the inner surface of the strap, said bracket having a forwardly extending portion, a member detachably secured to said bracket and having a depending friction finger for engaging the inner surface of said strap, said member having a transverse slot and a forwardly and rearwardly extending slot, an adjusting member having a threaded upper end extending through an opening in the forward portion of said bracket and through said forwardly and rearwardly extending slot in said member, said adjustment member having an eccentric at its lower end fitting into said transverse slot to cause forward and rearward movement of said member into adjusted position, and means for locking said adjusting member in adjusted position.
